UNITED STATES PATENT OFFICE.

JAMES L. DILLON, OF LEAVENWORTH, KANSAS, ASSIGNOR OF ONE-HALF TO FREDERICK L. WENDLER, OF ST. LOUIS, MISSOURI.

PIPE-VISE.

1,353,568.

Specification of Letters Patent. Patented Sept. 21, 1920.

Application filed November 25, 1919. Serial No. 340,617.

To all whom it may concern:

Be it known that I, JAMES L. DILLON, a citizen of the United States, residing at Leavenworth, in the county of Leavenworth and State of Kansas, have invented certain new and useful Improvements in Pipe-Vises, of which the following is a specification, reference being had therein to the accompanying drawings.

10 This invention relates to a device for holding pipe or similar articles or materials while being worked on, and it provides such a device so arranged that it can be mounted firmly on a bench or other base or support 15 without material alteration thereof.

One of the objects of the invention is so to form such a device that it will securely hold pipe or other round material, and also material of other shapes, of varying sizes 20 up to the maximum that can be taken by its jaws.

It also is an object of the invention to provide in such a device means whereby the material or article held may be brought 25 quickly between or against the jaws or equivalent parts and great leverage easily exerted in clamping in place what is held.

When read in connection with the description herein, the details of construction, 30 and arrangement of parts contemplated by the invention will be apparent from the accompanying drawings, forming part hereof, wherein an embodiment of the invention is disclosed, for purposes of illustration.

35 While the disclosures herein exemplify what now is considered to be a preferable embodiment of the invention, it is to be understood that it is not the intention to be limited necessarily thereto in interpretation 40 of the claims, as modifications and adaptations within the limits of the claims can be made without departing from the nature and spirit of the invention.

Like reference-characters refer to corresponding parts in the views of the drawings, 45 of which—

Figure 1 is a plan view;

Fig. 2 is a side elevation, partly in section on the line 2—2, Fig. 1;

50 Fig. 3 is an end elevation;

Fig. 4 is a sectional view on the line 4—4,

Fig. 2;

Fig. 5 is a sectional view on the line 5—5,

Fig. 2; and

55 Fig. 6 is a view of the handle member.

Having more particular reference to the drawings, 7 designates a flat base member arranged to be secured firmly to a bench or other suitable support by means of bolts or other fasteners disposed through holes 8 60 therein. A supporting member 9 is associated with and extends at an angle from the base member, the supporting member or standard being preferably a plate formed integrally with the base member and disposed at right angles with respect to the plane of that member. 65

One or more pairs of jaws 10 are secured to one side of the standard; their opposed edges or surfaces are inclined with respect 70 to the plane of the standard in such manner that the distance between them increases from the standard to their outer ends whereby a wedge-shaped space is afforded, and those edges or surfaces are formed with 75 teeth 11 or otherwise roughened to prevent slipping of the article or material held thereagainst.

In the embodiment of the invention disclosed herein, two pairs of such jaws are employed, and they are secured to the standard by integral pins 12 extending therethrough and having their heads upset against the face of the standard opposite to the jaws, but other numbers or pairs of jaws may be 85 used and secured to the standard in that or other suitable manner.

In order that the pairs of jaws and the members of each pair may be placed different distances from one another, and also to 90 provide for varying numbers of pairs, the standard may be formed with sets of differentially spaced and placed holes 13 and the jaws with pins 14 arranged to extend therethrough and to be held by nuts 15 on their 95 threaded ends, as shown by Fig. 4.

Two side members or plates 16, spaced from and in substantially parallel relation to each other, and constituting a frame for supporting operative parts of the device, 100 extend from the side of the standard opposite to the jaws, and each of these members has an integral laterally-extending flange 17 by which it is held on the standard by bolts or other suitable fasteners 18 extending therethrough. 105

Ordinarily, the frame will remain in the same place on the standard. However, in order to meet unusual requirements, as when the location of the pairs of jaws may be 110

changed, the standard may have a plurality of sets of holes 19, as seen in Fig. 4, for reception of fasteners 18, which will permit the shifting of the frame, or the employment of a plurality of frames and parts carried thereby if that is necessary.

A shaft 20 is journaled in the frame members 16 adjacent to the standard, and one or more winding members or wheels 21 are fast on that shaft. Each of these wheels has peripheral recesses or seats 22 conforming in shape and size to and arranged to take a flexible binding member such as a chain 23, abutments 22' engaging the links 15 lying flat and preventing the chain from slipping off the wheel.

One portion of the chain, as its end link, is made fast to any suitable portion of the device, as to a frame member by a fastener 20 24. When the device is in use, the free portion of the chain is extended over the article or material to be drawn against the jaws and over the wheel and into its seats, slots 25 permitting the chain to be disposed through the 25 standard.

The present embodiment of the invention contemplates employment of two chain-wheels 21, one on each end of the shaft 20 outside of the frame members, and two 30 chains, but a greater or less number may be used, if necessary. If more than two wheels and chains are used, the shaft 20 may be longer to accommodate them; and, if the shaft is so lengthened as to require support 35 in addition to that afforded by two frame members, one or more additional such members may be secured to the plate by fastenings through extra holes 9.

A gear 26 is fast on shaft 20 between the 40 frame members 16, and it is in mesh with an intermediate gear 27 rotatably mounted between those members on a shaft 28. A shaft 29 is carried by the frame members near their free ends, and a handle member 30 is 45 fulcrumed on that shaft between those members, the handle member having a toothed terminal segment 31 in mesh with the intermediate gear. The free ends of the frame members 16 are formed with teeth affording 50 segmental racks 32 for engagement with a detent 33 on the end of a slide 34, which latter is connected with a member 35 pivoted on the free end portion of the handle member, the detent being kept in engagement 55 with the racks by a spring 36 between the member 35 and the handle member.

When an article or material, such as a pipe for example, is to be held by the device, it is brought against or between the 60 jaws, and the chains are passed thereover and over the chain-wheels and into the seats thereof; or, if the chains already are in loop form and over the wheels, the article may be passed through the loops. The 65 handle member at that time is either in its

median position or swung toward the side on which the chains are disposed on the wheels. While the parts are in such positions, the chains are drawn against the held article as tightly as may be by hand. Then 70 the handle is swung, and by this movement, through the instrumentality of the segment and gears, the chain-wheels are rotated, the chains drawn more tightly against the article, and the latter clamped against or between the jaws. The detent and racks will prevent reverse movement of the handle and loosening of the hold on the article.

The chains may be released from tension 80 on the article by imparting reverse movement to the handle after releasing the detent from the racks by pressing the pivoted member 35 against the spring 36, and they may be further loosened thereafter by moving the chains in or from the peripheral 85 wheel-seats. Then the article may be withdrawn longitudinally from the device, or laterally therefrom after freeing the chains entirely from it.

Having thus described my invention, what 90 I claim as new, and desire to secure by Letters Patent, is—

1. A vise comprising a support, an article-engaging element on one side of said support, spaced arms extending from the 95 other side of said support, a winding member journaled on said arms, a flexible binding member arranged to be engaged with said winding member and to pull an article against said engaging element, and means 100 whereby said winding member is rotated.

2. A vise comprising a supporting member, an article-engaging member thereon, a rotatable shaft, a winding member fast 105 thereon, a flexible binding member arranged to be engaged with said winding member and to pull an article against said engaging member, a gear fast on said shaft, and a lever operatively connected with said gear.

3. A vise comprising a supporting member, an article-engaging member thereon, a rotatable shaft, a winding member fast thereon, a flexible binding member arranged to be engaged with said winding member 115 and to pull an article against said engaging member, a gear fast on said shaft, an intermediate gear in mesh therewith, a lever having teeth in mesh with said intermediate gear, and means for holding said lever against movement in one direction.

4. A vise comprising a standard, a jaw on one side thereof, a frame on the opposite side thereof, a shaft rotatable in said frame, a winding member fast on said shaft, a flexible binding member arranged to be engaged 125 with said winding member and to pull an article against said jaw, a gear fast on said shaft, an intermediate gear on said frame in mesh therewith, a lever having a toothed terminal in mesh with said intermediate 130

gears, and means for holding said lever against movement in one direction.

5. A vise comprising a standard, a pair of jaws on one side thereof, spaced plates 5 extending from the other side of said standard, a shaft rotatable in said plates, a winding member fast on said shaft, a flexible binding member fixed in one portion and arranged in another portion to be engaged 10 with said winding member and to pull an article against said jaws, a gear fast on said shaft between said plates, an intermediate gear in mesh therewith rotatably mounted between said plates, a lever pivoted between 15 said plates and having a toothed segment in mesh with said intermediate gear, and means

for holding said lever against movement in one direction.

6. A vise comprising a standard, a jaw on one side thereof, a frame at the opposite side having a rack thereon, a shaft rotatable in said frame, a winding member fast thereon, a flexible binding member arranged to be engaged with said winding member and to pull an article against said jaw, a gear 25 fast on said shaft, a lever operatively connected with said gear, and a spring-controlled detent on said lever in engagement with said rack.

In testimony whereof I affix my signature. 30

JAMES L. DILLON.
